No. 629,303.

Patented July 18, 1899.

H. POLICAN.

JACQUARD AND DOBBY CARD.

(Application filed Apr. 18, 1898.)

(No Model.)

UNITED STATES PATENT OFFICE.

HENRY POLICAN, OF PHILADELPHIA, PENNSYLVANIA, ASSIGNOR OF ONE-HALF TO JOHN ESSLER, OF SAME PLACE.

JACQUARD OR DOBBY CARD.

SPECIFICATION forming part of Letters Patent No. 629,303, dated July 18, 1899.

Application filed April 18, 1898. Serial No. 677,971. (No model.)

To all whom it may concern:

Be it known that I, HENRY POLICAN, a citizen of the United States, lately residing in Paterson, in the county of Passaic and State 5 of New Jersey, and now in the city and county of Philadelphia, in the State of Pennsylvania, have invented certain new and useful improvements in jacquard or dobbay cards and the art and means of connecting them to each 10 other in series, of which improvement I do hereby declare the following specification and the accompanying drawings are sufficiently full and clear to enable others skilled in the art to make and use the said invention.

This invention relates to the pattern-cards known as "jacquard" and "dobby" cards used in weaving machinery to control the operation of needles or wires that regulate the action of the jacquard-harness, through which 15 the warp-threads pass, so as to produce figures in the woven product, and relates particularly to the connecting of the cards together in flexible series, and has for its objects the more expeditious fastening of them, 20 greater durability of the connections, and better accuracy of register of the apertures in the several cards with the projecting points upon the weaving machinery whereby the cards are operated. To effect these objects, 25 this invention may be briefly stated to consist in making perforations in the cards in lines of uniform distances from the ends of the cards and connecting tapes coated on one side with adhesive cement to the cards upon opposite 30 sides of the cards on the lines of the perforations and applying pressure to the tapes, so that the tapes adhere to each other in the perforations and hold securely on the cards, and the tapes are also cemented to each other at 35 the interstices between the cards, forming 40 easily-flexible and durable hinges connecting the cards.

Heretofore the practice of connecting jacquard and dobbay cards has been by lacing or 45 sewing cords through apertures formed in them, which cords lengthened and shortened with hygrometric changes of the atmosphere and varied the distances between the cards and, besides being flexible in the direction of 50 the length of the cards, were susceptible of lateral motion, which produced undue wear

between the pins or points of the weaving-machine and the edges of the apertures in the cards, thus impairing the registering of the cards with the needles or wires of the loom 55 controlling the harness and seriously impairing the usefulness and durability of the cards. My invention to obviate these objections is made and practiced as follows, referring to the accompanying drawings, in which— 60

Figure 1 shows in flat view three cards as made to be united in series. Fig. 2 shows one of the cards in enlarged section on the line marked *xx* on Fig. 1. Fig. 3 shows in flat view three cards as united in series by tapes. 65 Fig. 4 shows an enlarged section of two of the cards so united, drawn in the plane indicated by the line *yy* on Fig. 3. Fig. 4^a shows in enlarged view a part of Fig. 4.

The cards (marked 1) are of the usual rectangular form, having apertures 2 for receiving the wires controlling the harness and warp-threads and apertures 3 for registering with pins on the cylinder of the loom which actuates them. In these respects they do not differ from cards as now in general use. Apertures 4 are made in lines across each card, and the cards are held in proper position of register with each other by means of the apertures 3, fitting on suitable pins. Tapes 6 70 and 7 are applied to opposite sides of the cards 1 on the lines of the apertures 4, with cement upon the opposed surfaces of the tapes, and pressed firmly upon the cards by elastic pressing pads or rollers 8 and 9, which force the 75 tapes 6 and 7 into contact with each other in the apertures 4, as shown in Fig. 4^a, and at the interstices 10 between the cards, where the tapes adhere firmly to each other and also adhere to the surfaces of the cards 1. The 80 tapes 6 and 7 form flexible hinges between the cards 1 at the points marked 11. The other portions of the tapes being connected firmly to the cards are unaffected as to length by 85 hygrometric changes of the atmosphere, and having no motion or friction between them and the edges of the cards, as is the case with lacing-cords, any inaccuracy and wear from 90 such causes are avoided.

The cement used should be such as will not 95 make the tapes rigid or brittle at the portion between the cards, and any cement having 100

strong adhesive properties with a flexible property answers. I have used a cement known commercially as "diachlon" or "lead-plaster" with satisfactory results.

5 The fastening of the cards together in the manner above described is most economically practiced by automatic machinery, which is the subject of a distinct application for Letters Patent.

10 Having described my invention, what I claim is—

As an improved article of manufacture, a

series of jacquard or dobby cards, having interspaces between the cards, lines of perforations through the cards, and tapes cemented 15 upon opposite sides of the cards, with adhesion of the tapes to each other in the apertures, and at the interspaces between the cards, as and for the purpose set forth.

HENRY POLICAN.
